A. R. STEPHEN,
HAND PICKING TABLE,
APPLICATION FILED APR. 4, 1921.

1,414,598.

Patented May 2, 1922.

UNITED STATES PATENT OFFICE.

ARCHIBALD R. STEPHEN, OF LODI, CALIFORNIA.

HAND-PICKING TABLE.

1,414,598.

Specification of Letters Patent.

Patented May 2, 1922.

Application filed April 4, 1921. Serial No. 458,399.

To all whom it may concern:

Be it known that I, ARCHIBALD R. STEPHEN, a citizen of the United States, residing at Lodi, county of San Joaquin, State 5 of California, have invented certain new and useful Improvements in Hand-Picking Tables; and I do declare the following to be a full, clear, and exact description of the same, reference being had to the accompanying 10 drawings, and to the characters of reference marked thereon, which form a part of this application.

This invention relates to improvements in picking tables such as are used in sorting 15 or picking over nuts, beans and other produce by hand after whatever mechanical or automatic equipment has been used as far as possible.

The principal object of my invention is 20 to provide a structure by means of which the picker may use both hands in picking or sorting the produce, thereby enabling such person to accomplish more in a given time than if one hand had to be otherwise 25 occupied.

A second object is to provide means for allowing the produce to pass continuously 30 past the picker, at a speed and volume which may be independently regulated by the operator so that he may do the necessary work in a thorough manner and according to his 35 capacity.

A further object is to provide a unit device, made portable if desired and independent 35 of any other equipment, which will have a common produce bin or source of supply, a plurality of tables each adapted to accommodate a single worker, and a common power means for operating the tables, each 40 of the latter however having individual speed and supply control means.

A further object of the invention is to produce a simple and inexpensive device and yet one which will be exceedingly effective 45 for the purposes which it is designed.

These objects I accomplish by means of such structure and relative arrangement of parts as will fully appear by a perusal of the following specification and claims.

50 In the drawings similar characters of reference indicate corresponding parts in the several views.

Fig. 1 is a side elevation of my improved structure, partly broken away as to its 55 length and height.

Fig. 2 is an enlarged end view, part being in section.

Fig. 3 is an enlarged fragmentary front view of a delivery chute, showing the control means.

60

Fig. 4 is a sectional view of the same.

Referring now more particularly to the characters of reference on the drawings, the numeral 1 denotes the floor or base beams of the structure, presuming the latter to be a 65 portable unit, these beams being positioned in parallel and suitably spaced alinement.

Projecting upwardly from the beams 1 are spaced uprights 2 supporting a combination bin and hopper 3, which tapers outwardly 70 from bottom to top on all sides.

Secured to the beams 1 between the uprights 2 are posts 4 capped by a beam 4^a, which aids in supporting the hopper or bin. The posts 4 support rigid horizontal arms 75 5, extending on both sides of the posts and parallel to the beams 1, making with said posts a T shaped structure, the height of the arms from the base being about the same as that of an average table, and there being as 80 many such posts and arms as it is desired to have tables.

Extending parallel to the arms 5 and in horizontal alinement therewith and spaced therefrom a desired distance are other and similar arms 6, supported by braces 7 or otherwise, between each corresponding pair of such arms there being rollers or pulleys 8 journaled therein, these rollers being positioned adjacent each other at the center of 90 length of the arms and connected to turn in opposite directions by gears 9. One of each of said pulleys has a common drive shaft 10 extending therebetween, which is adapted to be rotated at a certain and preferably 95 low speed by a belt and motor drive or otherwise as indicated at 11, or each set of pulleys may be turned by a common motor by means of straight and crossed belts, without the use of the gears 9.

At the outer ends of and between pairs of the arms 5 and 6 are idler pulleys 12, while endless belts 13 of canvas or similar material passes over each pair of pulleys 8 and 12, there being a flat board or floor 14 105 under the top run of the belt, while the arms 5 and 6 project thereabove to form a guard rail.

Tension rollers 15 are mounted on arms 16 under the belts and normally bear there- 110

against by reason of springs 17, these rollers being arranged to be withdrawn from contact with the belts by means of pedals 18 operatively connected to the arms.

5 By suitable manipulation of any pedal therefore, the tension roller may be slackened so as to reduce the frictional contact of the belt with its drive roller, and so reduce the speed of the belt or eliminate its 10 movement entirely. Also it permits both hands of the worker being used on the belt, the speed being controlled entirely by the foot.

This construction enables a worker to sit 15 alongside each run of belt 14 on the side thereof opposite the main supporting post 4, with plenty of room to sit thereat and allow the legs to project thereunder.

The belts are connected to be driven so that 20 their upper surfaces move in opposite directions and outwardly, so that the picked produce may drop into boxes 19 placed under the outer rollers 12.

An individual supply of produce from 25 the bin for each belt is had by means of angled chutes 20 terminating closely against the belts at the inner ends thereof. The forward end of each chute is cut away from the bottom a certain distance as shown at 21, this 30 opening being covered by flexible fingers 22, to the outside of which is fixed a sheet 23 of tin or other material, which is arranged to be adjusted so that the length of the fingers, and hence the flexibility thereof, may be adjusted.

The finger member and the plate 23 are adapted for vertical movement as a unit, so that they may be raised clear of the opening 21 to allow the products to have an un- 40 obstructed flow onto the belt. This may be done by means of a stud 23 fixed to the chute and projecting through slots 25 in the members 22 and 23, the stud having a clamping nut 26 on the outer end thereof and the plate 45 23 having a finger-hook 27 thereon.

An independent closure plate 28 is provided for each chute, so as to be able to entirely cut the flow from the bin to each chute at will. These plates are so positioned 50 so that no pockets are formed, so that when any chute is shut off, all the products in the bin may be withdrawn from the others.

By reason of the angling of the chutes, and the use of the flexible fingers, the products will be held from passing onto the belt in too great a volume, and yet will not jam and clog the chute.

From the foregoing description it will be

readily seen that I have produced such a device as substantially fulfills the objects of 60 the invention as set forth herein.

While this specification sets forth in detail the present and preferred construction of the device, still in practice such deviations from such detail may be resorted to as 65 do not form a departure from the spirit of the invention, as defined by the appended claims.

Having thus described my invention, what I claim as new and useful and desire to secure by Letters Patent is:—

1. In combination with a driven belt, a chute positioned thereabove and terminating therat, an opening provided in the front end of the chute and extending upwardly a 75 certain distance from the lower edge, flexible fingers covering said opening, and means for altering the operative length of said fingers.

2. In combination with a driven belt, a chute positioned thereabove and terminating therat, an opening provided in the front end of the chute and extending upwardly a certain distance from the lower edge, flexible fingers covering said opening, 85 means for altering the operative length of said fingers, and independent means for raising the fingers clear of the chute-opening, without disturbing the finger-length adjustment.

3. In combination with a driven belt, a chute positioned thereabove and terminating therat, an opening provided in the front end of the chute and extending upwardly a certain distance from the lower edge, flexible fingers forming a unit member covering said opening, a rigid plate secured in front of and to the finger member and adjustable vertically thereon, and means for adjusting the plate and finger member as a unit relative to the chute-opening.

4. In combination with a driven belt, a chute positioned thereabove and terminating therat, an opening provided in the front end of the chute and extending upwardly a certain distance from the lower edge, flexible fingers covering said opening, a rigid plate secured on the finger member and adjustable vertically thereon, a stud fixed on the chute and projecting through aligned and vertical slots in the plate and finger member, and a clamping nut on the outer end of said stud.

In testimony whereof I affix my signature.

ARCHIBALD R. STEPHEN.
